DECORATIVE SCREEN OR THE LIKE

Charles M. Goodman, Alexandria, Va., assignor to Reynolds Metals Company, Richmond, Va., a corporation of Delaware

Filed Dec. 29, 1961, Ser. No. 68,127

Term of patent 14 years

(Cl. D54—2)

I claim:

The ornamental design of a decorative screen or the like, substantially as shown and described.
